(57) **CLAIM**

The ornamental design for a toothbrush head, as shown and described.

DESCRIPTION

FIG. 1 is a top, left side perspective view of a toothbrush head of my new design;

FIG. 2 is a left side elevation view thereof;

FIG. 3 is a front elevation view thereof;

FIG. 4 is a right side elevation view thereof;

FIG. 5 is a top view thereof;

FIG. 6 is a bottom view thereof; and,

FIG. 7 is a back view thereof.

In FIG. 1, the handle of the toothbrush is shown in broken lines for illustrative purposes only and forms no part of the claimed design.
